(57) **CLAIM**

I claim the ornamental design for a drink and food adapter tray, as shown and described.

DESCRIPTION

FIG. 1 is a perspective view of a drink and food adapter tray showing my new design. The broken line portion is for illustrative purposes only and forms no part of the claimed design;

FIG. 2 is a top plan view thereof;

FIG. 3 is a bottom plan view thereof;

FIG. 4 is an elevational view of one side thereof;

FIG. 5 is an elevational view of the other side thereof;

FIG. 6 is an elevational view of one end thereof; and,

FIG. 7 is an elevational view of the other end thereof.
